FLUID-TREATING DEVICE.

1,088,086.

Specification of Letters Patent.

Patented Feb. 24, 1914.

Application filed June 14, 1913. Serial No. 773,652.

To all whom it may concern:

Be it known that I, FRED R. MONROE, a citizen of the United States, and a resident of Middletown, in the county of Orange and 5 State of New York, have invented certain new and useful Improvements in Fluid-Treating Devices, of which the following is a specification.

My invention relates to apparatus for the 10 germicidal treatment of fluids in general, and the construction thereof is so designed as to adapt it especially for the heating or cooling of milk, in order to destroy bacteria and other micro-organisms which the liquid 15 may contain.

A preferred embodiment of my invention is illustrated on the accompanying drawings, which are a part of this specification, and upon which the same characters of reference indicate the same parts throughout the several views.

On said drawings: Figure 1 is a vertical transverse section of my apparatus; taken on the line 1—1 of Fig. 2; Fig. 2 is a 25 plan of the same with the lid or cover removed; Fig. 3 is a side elevation, showing an outside view of my device; Fig. 4 is a 30 view of a detail forming one of the inner parts of my invention; Fig. 5 is a similar view showing another detail; Fig. 6 is a perspective view of the spreader which distributes the fluid treated in my invention; and Fig. 7 is a horizontal section of the 35 removable bottom of my fluid treating device.

To describe the invention shown by the drawings in detail, I employ the numeral 1 to indicate a casing to which the fluid or liquid to be treated, such as milk, is supplied by a pipe 2. The fluid enters the casing by 40 an opening 4 in the lid or cover 3. As will be readily understood the pipe 2 may have any kind of controlling valve, and the lid be provided with handles 3' to remove the same. This lid has a peripheral flange 3^a which engages a similar flange around the upper rim of the casing 1, and the two flanges are held together without packing by bolts or other fastening means. The end of the pipe 2 may simply project through the opening 4, 45 or a packed joint may be employed if desired. After entering the casing the fluid encounters a distributor 5 which spreads it, and flows through a central group of tubes 6 into a chamber 7 at the lower part of the casing 1. From this chamber it returns by

other tubes 6 surrounding the first tubes to the upper part of the casing and passes out by a pipe 8. This pipe 8 leads to a conduit 9, and this conduit 9 is joined by a pipe 10 to the chamber 7 to enable the chamber 7 to be drained. A suitable valve 33 controls the communication of the conduit 9 with the pipes 8 and 10. 60

The fluid has its temperature affected either by raising or lowering as it passes through the casing, and for this purpose I provide the casing 1 with a main chamber 11 which surrounds all the tubes 6. I also provide the casing with a removable hollow bottom 12, which communicates with the chamber 11. The agent for heating or cooling enters the chamber 11 and passes therefrom into the bottom 12, and thus the fluid is acted upon not only while it is in the tubes, but in the chamber 7 also. 65 70 75

The casing 1 is provided with a plate 13, forming a top, which is lowered below the level of the upper edge of the casing; and another plate 14, above the lower edge of the casing. Between these two plates the chamber 11 is located, as will appear from an inspection of Fig. 1. The upper plate has a raised central section 15 and a peripheral section 16, and a rim or flange 17 surrounds the section 15 to prevent fluid 80 from flowing from the section 15 directly to the section 16. These plates 13 and 14 hold the tubes 6 in position by means of apertures into which the upper and lower ends of the tubes are inserted. As will be understood the tubes 6 pass through the chamber 11, but do not communicate therewith. 85 90

As shown upon Fig. 1 the section 15 has its surface depressed around the central group of tubes 6, which have perforations 95 19 adjacent the depressed portions, so that fluid after passing the spreader or distributor enters the tubes through these perforations. Each of the tubes 6 receives an inner tube 20, the upper end of which has a head 100 21. These heads rest upon the upper ends of the tubes 6, closing the same, and holding the inner tubes in position. The inner tubes may have any means such as projections or ribs 20' to keep them centrally of the tubes 6, so as to separate their adjacent surfaces and form a space or passage. This arrangement causes the fluid in the tubes 6 to be spread out in a thin film on the inner surfaces of the tubes 6 and be more susceptible 105 110

to a cooling or heating action. Similar tubes 20 are placed in the tubes surrounding the central group of tubes 6, and these inner tubes for the remaining tubes 6 have heads 23 which enter the outer tubes. These heads 23 may have any suitable means such as projections from their sides to prevent them from entering tubes 6 too far, and they also have notches or recesses 24 to enable fluid to 10 pass out of the tubes, these notches forming ports for the passages between the inner and outer tubes. The inner tubes here referred to will of course have means to hold them in central position with respect to the 15 outer tubes, the same as above. The inner tubes for all the tubes 6 merely serve to keep the fluid in contact with the inner surfaces of the tubes 6, to enable me to cool or heat the fluid in the most efficient manner. I 20 may therefore make these members in the shape of tubes 20 as shown, or in the shape of solid rods, if desired. I prefer to make them in the shape of tubes, however, and I provide the heads 21 and 23 with short 25 pipes 22 to admit air into them. The upper ends of these pipes 22 are turned down, to prevent fluid getting to the inside of the tubes 20.

To make the spreader or distributor 5 which distributes fluid to the inner group of tubes 6, I employ a sheet of metal or other suitable material 25, having legs 26. This piece is preferably stamped, and is made so that its center is highest. Between 30 the center and the periphery are corrugations 27, and apertures 28. These corrugations retard the fluid and cause it to pass through the apertures as will be readily understood. On the top of the spreader I place 35 a cup-shaped body 29, having perforations 30 near the bottom of the same. This body is centrally located, and is placed so as to be directly beneath the end of the pipe 2. It receives the incoming fluid or other 40 liquid, forms a pool, which in the case of milk prevents splashing or other agitation, and by means of the openings 30 causes the fluid to pass out on all sides of the same and flow all over the surface of the member 45 25. This cup-shaped member is shown as made separate, but it may be made integral with sheet 25, as by forming a depression in the center, and omitting the openings 30. It may also be made in the shape of an 50 up-standing rim or flange with the perforations included. The spreader is further provided with peripheral projections 26' to center it on the section 15. To conduct the fluid from the casing I employ the pipe 8 as above noted, and I locate a thermometer 31 in this pipe to register the temperature of the fluid after treatment. This pipe 8 also includes a glass or other transparent section 32, so 55 that any impurities may be seen as the fluid flows out. Communication between the con-

duit 9 and the pipes 8 and 10 is controlled by a valve 33. To supply a heating or cooling agent to the chamber 11, I locate two coils of pipe 34 therein, one at the top and the other at the bottom. These coils are 70 perforated, and each is connected to a steam pipe 35 and a water or brine pipe 36. A valve 37 controls these pipes, and from the valve to the coils 34 leads a pipe 38. A drain connection 39 may be added if desired. The valve 37 permits either of the pipes 35 or 36 to supply the coils 34, and permits the coils to be drained when necessary. 75

Communication with the bottom 12 is 80 established by a pipe 40, which has its upper end bent up into proximity with the highest part of the chamber 11, terminating just below the section 15, and having a perforated cap 41 to close the end. This pipe passes out through the side of the casing and is joined to a pipe 42. This pipe 42 makes a slip-joint connection with a bent-up pipe 43 leading to the inside of the removable bottom section 12, and from this bottom the 85 contents are drained by way of a connection 44. This connection may be bent up, so that the contents of the bottom may never sink to a low level. The slip-joint may be 90 of any desired type that will enable the lower end of the pipe 42 to be received by the pipe 43 and prevent leakage. This kind of joint enables the bottom to be readily separated from the casing. 95

To hold the bottom on the casing I provide the latter with a flange 46, and the bottom with a matching flange 47. The flange 47 is grooved over its whole extent, to receive packing 48, and the two flanges are securely held together to obviate any leakage 100 between the flanges. I also provide the bottom with baffle plates 45, which are substantially V-shaped in arrangement, and placed so as to divert the incoming cooling or heating agent and prevent it from flowing directly through the bottom and out at the pipe 44. I also provide the casing with legs 49, preferably three in number at the sides, and the dimensions of the bottom will be such that the bottom can be drawn out 105 between any two of the legs when the bottom is to be removed. A drain cock 50 for the bottom and a draincock 51 for the chamber 11 are added to enable contents to be 110 quickly removed when necessary. 115

From this description the manner of operation, utility and advantages of my invention will be clear. The fluid enters at the opening 4, passes over the spreader 5 and into the central tubes 6, down into chamber 7, and up through the other tubes 6 to the outlet pipe 8. Owing to the fact that the section 15 is higher than the section 16 the substance treated, such as milk, flows down to the chamber 7 and up to the outlet under its 120 125 130

own head, and no pumps or other devices to force the milk through the casing are needed. The outlet 8 is placed as near the level of the section 16 as possible. If the milk or other liquid is to be heated, the valve 37 is turned to supply water to the chamber 11, and then to supply steam to heat the water. The chamber 11 and bottom 12 thus become filled with water at the required temperature and it will be observed that the bottom does not fill with overflow from the chamber 11 till the water therein rises almost to the level of the section 15. This is because of the upturned end of the pipe 40. The milk is thus subjected to the action of heat in the tubes 6 and in the chamber 7, and the action of the device is rapid and efficient. If, however, the milk or other liquid is to be cooled instead of heated, brine is run into the chamber 11 from the pipe 35 to the perforated coils 34, and the chamber and bottom then become filled with a cooling agent instead. The action is the same in both cases. A suitable thermometer can be joined to the pipe 38, to register the temperature of the agent entering the chamber

11. The milk or other fluid can be withdrawn from the casing by way of the pipe 10 instead of the pipe 8 if desired, or partly 30 by way of pipe 8 and partly by way of pipe 10. If any impurities are in the milk they will be seen through the section 32, and the apparatus can then be stopped till the cause of the trouble is ascertained and removed. Ordinarily the milk will all be withdrawn 35 through the pipe 8 and the pipe 10 used only at the end of the process to drain the chamber 7. The chamber 11, as above stated, can be drained by the cock 51 and the bottom by the cock 50. The slip joint 40 between the pipes 42 and 43 enables the bottom to be readily removed and replaced, and as shown, the bottom 12 will have suitable handles and casters to enable the same to be 45 easily moved about.

My apparatus is exceedingly efficient, yet simple in construction, and it can readily be cleaned by taking off the cover 3, bottom 12, and removing the inner tubes 20. The parts 50 will be of suitable materials, and I prefer to make the plates 13 and 14 of sufficiently heavy stock to enable them to support the tubes 6. All the piping will be of sanitary design, with elbow and T couplings, to 55 enable it to be taken apart for cleaning purposes.

It will be understood of course that the milk or other fluid will not be fed in too rapidly, and that the central tubes 6 will be 60 in such numerical ratio to the balance of the tubes 6 that there will be no overflow at the flange 17.

I prefer to admit air through the short pipes 22 to the inner tubes 20 because if the 65 heads 21 and 23 be entirely imperforate, the

action of the milk, in case the chamber 7 fills up and the level of the milk rises above the top of the chamber in the tubes 6, will tend to draw the air in the tubes 20 out of the same by aspiration or suction. In this way 70 a partial vacuum will be produced, and a column of milk will be maintained by atmospheric pressure in each inner tube as long as the general level is above the top of the chamber 7 or bottom of the tubes 20. 75 These columns of milk in the inner tubes will be higher than the level of the milk in the outer tubes 6 and will in a measure be shielded from the action of the heating or cooling agent in the chamber 11 and the 80 action of the device interfered with. The short open pipes 22 prevents the formation of these columns by exposing any milk in the tubes 20 to atmospheric pressure, and when the general level of the milk in chamber 85 7 falls below the top of the chamber 7, any milk in the tubes 20 will flow out. By continuing the flange 17 up to the cover 3 and providing suitable packing I can even adapt my apparatus for the treatment of 90 gases.

I wish to have it understood that I do not limit myself to the exact arrangement of parts shown on the drawings and described in this specification. On the contrary I desire to reserve to myself the right to make whatever changes in the shape, size and arrangement of the parts fairly fall within the scope and spirit of my invention.

I claim—

1. In a fluid treating device, the combination of a tube, a member loosely received by the tube, the said tube and member being separated from each other to form a space or passage between them, and means for holding a temperature-changing medium in contact with said tube.

2. In a fluid treating device, the combination of a hollow outer member having one or more perforations to admit fluid, an inner member loosely received by the outer member and separated therefrom to form a space or passage, said inner member having a head to close the outer member, and means for holding a temperature-changing medium 105 in contact with said outer member.

3. In a fluid treating device, the combination of a hollow outer member, an inner member received by the outer member and separated therefrom to form a space or passage, and a head carried by the inner member to close the outer member, said head having notches forming ports for the passage.

4. In a fluid treating device, the combination of a hollow outer member, a hollow inner member loosely received by the outer and separated therefrom to form a space or passage, said inner member having a head to close the outer, said head having means for 125 130

admitting air to the inner member, and means for holding a temperature-changing medium in contact with the outer member.

5. In a fluid treating device, the combination of a hollow outer member and a hollow member received by the outer and separated therefrom to form a space or passage, said inner member having a head to close the outer and a short pipe secured to the head 10 to admit air to the inner member, the said pipe being bent on itself.

6. In a fluid treating device, a distributor having means for receiving fluid and spreading the same radially outward from the central axis of the distributor, the distributor also comprising a member located substantially in the plane of flow of the fluid and extending outward beyond the periphery of said means, said member receiving fluid 15 from said means and substantially preventing axial flow as long as the fluid remains in contact with the member, said member having spaces to permit the fluid to pass through it.

25 7. In a fluid treating device, a distributor having a top provided with corrugations for retarding fluid to be distributed and a plurality of spaces between the corrugations to permit fluid to pass through the same.

30 8. In a fluid treating device, a distributor having a perforated cup-shaped central portion to receive and spread fluid and a corrugated peripheral portion to retard fluid after spreading, said distributor having a 35 plurality of spaces to permit fluid to pass through the same.

40 9. In a fluid treating device, the combination of a casing having internal transverse partitions forming with the walls of the casing a chamber, one partition being spaced from the adjacent end of the casing to form a second chamber, a hollow closure for said end, said closure being removable, conducting means passing through the first chamber 45 into the second, whereby the contents of the second chamber and said means can be affected by the contents of the first chamber and the closure without being brought into contact therewith, and connections including 50 a slip joint between the first chamber and the closure permitting the ready removal of the closure.

55 10. In a fluid treating device, the combination of means for forming a chamber having one part of its top higher than the remainder of the top, an overflow conduit entering the chamber and having its end bent up into proximity to the highest point of the top, and means forming a continuous

passage extending through the raised part 60 to and through the remainder of the top.

11. In a fluid treating device, the combination of a casing having one end inclosing a chamber, means for admitting fluid at the opposite end, means for conducting fluid to 65 the chamber, means for conducting fluid from the chamber back to the opposite end, and means for subjecting both the conducting means and the chamber to the action of a medium adapted to affect the temperature 70 of the fluid.

12. In a fluid treating device, the combination of a casing having a top with a central section higher than the peripheral section, a rim or flange surrounding the central 75 section, means for supplying fluid to the central section, means for conducting the fluid to the peripheral section before passing out of the casing, and means for subjecting the conducting means to the action of a 80 medium for affecting the temperature of the fluid.

13. In a fluid treating device, a casing having a lowered top comprising a section higher than the rest of the top, a spreader on 85 said section, means for supplying fluid to the spreader, means for conducting the fluid through the section to the remainder of the top, means for preventing the direct flow of the fluid from said section to the remainder 90 of the top, and means for subjecting the conducting means to the action of a medium for affecting the temperature of the fluid.

14. In a fluid treating device, the combination of a casing having a plurality of supports and a removable section at the bottom of the casing, the dimensions of the section permitting it to be removed between the supports.

15. In a fluid treating device, the combination of a casing having a chamber at one end extending across substantially the whole of said casing, means for admitting fluid at the opposite end of the casing, means for conducting the fluid to the chamber and 105 from the chamber, said conducting means communicating with substantially every part of the chamber, and means for subjecting both the chamber and the conducting means to the action of a medium for affecting 110 the temperature of the fluid.

Signed at Sussex in the county of Sussex and State of New Jersey this sixth day of June A. D. 1913.
